UNITED STATES PATENT OFFICE.

CARL A. CARLSON, OF BARBERTON, OHIO, ASSIGNOR TO THE DIAMOND MATCH COMPANY,
OF CHICAGO, ILLINOIS, A CORPORATION OF ILLINOIS.

COMPOSITION-APPLYING MECHANISM FOR MATCH-MACHINES.

No. 880,354.

Specification of Letters Patent.

Patented Feb. 25, 1908.

Application filed June 18, 1907. Serial No. 379,646.

To all whom it may concern:

Be it known that I, CARL A. CARLSON, a citizen of the United States, residing at Barberton, in the county of Summit and State 5 of Ohio, have invented certain new and useful Improvements in Composition-Applying Mechanism for Match-Machines, of which the following is a specification.

This invention relates to improvements in 10 composition-applying mechanism for match making machines of that class, more especially, in which rows of splints are introduced to a traveling endless carrier and transported thereby through appropriate dipping and 15 drying paths to a match-discharging station.

A machine of the class mentioned, embodying in its organization composition-applying mechanism, is set out in Letters Patent of the United States No. 528,457, 20 dated October 30, 1894, to Beecher & Wright, which mechanism includes in its construction a composition-vat, within which are rotatably mounted a composition mixer and a composition-applying roller, together 25 with differential driving devices therefor, whereby when the match machine is in actual operation, the said mixer and roller are rotated at a normal speed to effect, respectively, the intimate mixing of the composition 30 and the uniform application thereof to the ends of the depending splints on the traveling match carrier, and whereby, when the machine is stopped, the said mixer and roller are rotated at a relatively slow speed 35 to continue the stirring of the composition and thus prevent its settling and thickening within the vat and upon the roller, as will more fully appear by reference to said Letters Patent.

40 The object, primarily, of the present improvements is to simplify the construction and organization of the differential driving mechanism of the said patent, while retaining the important and practical advantages 45 thereof; and with this, and other objects in view, the improvements, stated generally, consist in providing the driving member for the mixer and roller with two loosely-mounted wheels, one of which is constantly driven 50 at a relatively slow speed from a convenient source of power, and the other of which is

driven at a normal speed from a moving element of the match machine, and in providing such member with a ratchet wheel, with the teeth of which engage two pawls on 55 said loosely-mounted wheels, respectively, together with various novel features of construction which will be hereinafter fully described and particularly claimed.

In the drawings—Figure 1 is a side elevation, partly in section, of composition-applying mechanism embodying my invention, a portion of the match carrier and actuating devices therefor being shown. Fig. 2 is a plan. Fig. 3 is a longitudinal vertical section, enlarged, through the pawl and ratchet devices, and adjuncts, for the mixer actuating shaft. Fig. 4 is a transverse vertical section, as on the line 4—4 of Fig. 3.

5 designates a suitable frame within which 70 is supported a tank 6 having hollow walls to afford a steam or hot water jacket, and 7 a composition vat resting upon the side walls of the tank and depending thereinto. The ends of the tank are open to permit the 75 ready application or removal, endwise, of the vat to or from the tank, as occasion may require.

8 designates an open frame, constituting a mixer, which is mounted to rotate within the 80 lower portion of the vat; and 9 a composition-applying roller which is mounted to rotate within and slightly above the upper portion of the vat. The shafts 10, 11 of the mixer and roller, respectively, are journaled 85 in suitable bearings in the end walls of the vat. These shafts are squared, or otherwise appropriately shaped, at one end of the vat, so as to couple readily with the correspondingly socketed hubs of intermeshing gear 90 wheels 12, 13, respectively, when the vat is slid endwise into the tank. The shafts 14, 15 of these wheels are mounted to rotate in suitable bearings on the frame 5; the shaft 14 being prolonged and having a bearing for its 95 outer end in a bracket 16 on the frame.

When the vat has been applied to the tank, motion properly imparted to the shaft 14 is transmitted therefrom through the intermeshing gear wheels to the mixer and 100 roller.

17 designates one of the transverse driven

shafts carrying the actuating gear wheels 18 for the endless match carrier 19, a part only of which latter is indicated in the drawings.

The several parts above referred to are substantially similar in construction, and operation with the corresponding parts set out in the Beecher and Wright patent aforesaid, and they, therefore, require no further or detailed description herein.

10 Loosely mounted on the shaft 14 is a bevel gear wheel 20 which meshes with a bevel pinion 21 fast on a vertical shaft 22, the latter being connected through intermeshing bevel wheels 23 with a suitably-disposed 15 counter shaft 24. This counter shaft is equipped with a pulley 25, which is belted with a line shaft (not shown), and hence, by virtue of the relative proportions of the gearing, the bevel wheel 20 is continuously rotated at a relatively slow speed.

On the shaft 14 is keyed, or otherwise secured, a wide ratchet wheel 26 with the teeth of which engage two pawls 27, 28, which are pivotally mounted on the inner sides of two 25 sprocket wheels, 29, 30, respectively. Springs, as 31, secured to the pivot pins of the pawls and to the sides of the respective sprocket wheels hold the pawls normally in engagement with the ratchet teeth.

30 The sprocket wheel 29 is conveniently connected by means of a chain 32 with a sprocket wheel 33 on the driven shaft, 17, for the carrier of the match machine, which latter wheel is positively driven from a suitable 35 source of power in the usual manner. Hence, during the operation of the match machine, the sprocket wheel 29 is driven at a normal rate of speed and, through the action of the pawl 27 on the ratchet wheel 26, the shaft 40 14 is correspondingly rotated; the motion of said shaft being conveniently transmitted therefrom through the gear wheels 12, 13, to the mixer and roller, respectively. During this operation, the bevel wheel 20 and 45 its sprocket 30 are continuously rotated from the line shaft, but as their speed is less than that of the sprocket wheel 29 the ratchet wheel turns in advance of, and is practically unaffected by, the pawl 28. 50 When, however, the match machine is thrown out of operation, the sprocket wheel 29 and its pawl 27 are idle, and, in consequence, the pawl 28 on the slowly rotating sprocket wheel 30 accomplishes the rotation 55 of the ratchet wheel and its shaft 14 with a corresponding movement of the mixer and roller so as to stir the composition and prevent it from settling and thickening within the vat and upon the roller.

60 It will be obvious that the power may be transmitted to the sprocket wheel 30 by means of a chain driven from any constantly moving source, in which case the bevel gear

connections may be dispensed with; and, further, that the pawl 28 may be pivoted to 65 the side of the bevel wheel, in which case the sprocket wheel 30 may be omitted. The sprocket wheel 30 and the described bevel gear mechanism however, are employed, in order that such wheel may be connected 70 through a suitable chain, as 34, with an overlying shaft leading to, and geared with, other composition-applying devices on the machine, when plural composition devices are employed, as for example, in the production 75 of so-called double-dipped matches.

I claim—

1. The combination with a composition vat, a rotary composition-applying roller, and a mixer, of gearing between said roller 80 and mixer, a shaft for actuating said gearing, two wheels loosely mounted on said shaft, means for driving said wheels at different speeds, a ratchet fast on said shaft, and pawls on said wheels engaging the ratchet, whereby 85 the said ratchet and shaft are driven by the pawl rotating at the higher speed, while that is turning, and by the pawl rotating at the lower speed pawl when the other stops.

2. The combination with a composition 90 vat, a rotary composition-applying roller, and a mixer, of two intermeshing gear wheels with which the shafts of said roller and mixer are adapted to be connected, two wheels loosely mounted on the shaft of one of said 95 gear wheels, means for driving said wheels at different speeds, a ratchet fast on said gear shaft, and pawls on said wheels engaging the ratchet, whereby the said ratchet and gear shaft are driven by the pawl rotating at 100 the higher speed, while that is turning, and by the lower speed pawl when the other stops.

3. The combination with a composition vat, a rotary composition-applying roller, and a mixer, of two intermeshing gear wheels 105 with which the shafts of said roller and mixer are adapted to be connected, two spaced sprocket wheels loosely mounted on the shaft of one of said gear wheels, means for driving said sprocket wheels at different 110 speeds, a ratchet wheel fast on said gear shaft in the space between the sprocket wheels, and pawls on the inner sides of said sprocket wheels engaging the ratchet, whereby the said ratchet and gear shaft are driven 115 by the pawl rotating at the higher speed, while that is turning, and by the lower speed pawl when the other stops.

4. The combination with a traveling carrier and actuating devices therefor, of a composition vat, a rotary composition-applying roller, and a mixer in said vat, gearing between said roller and mixer, a shaft for actuating said gearing, two spaced wheels loosely mounted on said shaft, operative connections 120 between one of said wheels and the actuating 125

devices for the carrier, means for constantly driving the other wheel at a relatively low rate of speed, a ratchet fast on said shaft in the space between the wheels, and pawls on said wheels engaging the ratchet.

In testimony whereof, I have signed my name to this specification in the presence of

two subscribing witnesses, this 12th day of June 1907.

CARL A. CARLSON.
